UNITED STATES PATENT OFFICE.

CHARLES AUGUSTUS OVERTON, OF COEUR D'ALENE, IDAHO.

ROOF-JOINT.

1,170,931.

Specification of Letters Patent.

Patented Feb. 8, 1916.

Application filed June 7, 1915. Serial No. 32,615.

To all whom it may concern:

Be it known that I, CHARLES A. OVERTON, a citizen of the United States, residing at Coeur d'Alene, in the county of Kootenai and State of Idaho, have invented certain new and useful Improvements in Roof-Joints, of which the following is a specification.

This invention relates to devices for forming a water-tight joint between a roof and a soil or other pipe passing therethrough.

The invention has for its object to provide a device of the kind stated which is easy to adjust to fit pipes of different diameters, and which grips the pipe so as to make a strong, durable and tight joint.

The object stated is attained by means of a novel combination and arrangement of parts to be hereinafter described and claimed, reference being had to the accompanying drawing in which—

Figure 1 is a side elevation showing the application of the invention; Fig. 2 is a plan view thereof; Fig. 3 is a cross-section 25 on the line 3—3 of Fig. 2, and Fig. 4 is front elevation.

Referring specifically to the drawing, 5 denotes a frusto-conical sleeve of sheet metal, having secured to its base an outstanding flange 6 whereby it is secured to the roof in any suitable manner. The base of the sleeve is cut slanting which places the flange at a corresponding angle, so that the device may be applied to a sloping roof. 35 For flat roofs, the sleeve will be arranged perpendicular to the base flange. The diameter of the sleeve is such that the soil or other pipe 7 may pass therethrough.

In the lower side of the sleeve 5 is a recess which is closed by a tongue 8, and from the bottom portion of this recess extends upward a sheet metal tongue 9 which is inside the tongue 8. These two tongues are curved transversely to conform to the curvature of the sleeve, and the tongue 8 laps the tongue 9. The tongue 8 is riveted or otherwise secured to the tongue 9, and the latter is formed integral with the sleeve 5. The width of the tongue 8 is such that it laps the inner surface of the sleeve for a short distance on opposite sides of the recess, and the side edges of said tongue, near the bot-

tom thereof, have notches 10 to receive the adjacent edges of the recessed portion of the sleeve. 55

On opposite sides of the recess in the sleeve 5 which is covered by the tongue 8, at the top of the sleeve, the latter has outstanding ears 11 provided with alined perforations to receive a clamping bolt 12 secured by a nut 13. Upon drawing the ears together the sleeve 5 is contracted and that portion which laps the tongue 8 is drawn tightly over the same and forces said tongue firmly against the tongue 9. The sleeve and 65 the tongues may thus be contracted or drawn tight around the pipe 7 to make a water-tight joint, and the parts are also adjustable for pipes of different diameters, within certain limits. The sleeve and the 70 tongues are of course flexible so that the overlapping parts may be clamped together as described.

I claim:

1. A roof joint comprising a flexible 75 sleeve having a side recess and a tongue extending upward from the bottom of the recess, a flexible tongue secured to the sleeve to cover the recess, said tongue lapping the inner surface of the sleeve at opposite sides 80 of the recess and also lapping the first-mentioned tongue, and means for contracting the sleeve to clamp the aforesaid lapping parts together.

2. A roof joint comprising a flexible 85 sleeve having a side recess and a tongue extending upward from the bottom of the recess, a flexible tongue secured to the sleeve to cover the recess, said tongue lapping the inner surface of the sleeve at opposite sides of the recess and also lapping the first-mentioned tongue, the side edges 90 of the flexible tongue having notches at its lower end in which the edges of the recessed portion of the sleeve seat, and means 95 for contracting the sleeve to clamp the aforesaid lapping parts together.

In testimony whereof I affix my signature in presence of two witnesses.

CHARLES AUGUSTUS OVERTON.
